UNITED STATES PATENT OFFICE.

HARRY T. GOSS, OF RUTHERFORD, AND JAMES W. BRYCE, OF BLOOMFIELD, NEW JERSEY, ASSIGNEES TO INTERNATIONAL TIME RECORDING COMPANY OF NEW YORK, OF ENDICOTT, NEW YORK, A CORPORATION OF NEW YORK.

TIME-RECORDER AND METHOD OF RECORDING ELAPSED TIME.

1,218,995.

Specification of Letters Patent. Patented Mar. 13, 1917.

Application filed January 25, 1912. Serial No. 673,404.

To all whom it may concern:

Be it known that we, HARRY T. Goss, a citizen of the United States, and resident of Rutherford, county of Bergen, and State of New Jersey, and JAMES W. BRYCE, a citizen of the United States, and resident of Bloomfield, county of Essex, and State of New Jersey, have invented a new and useful Time-Recorder and Method of Recording Elapsed Time, of which the following is a specification.

Our invention relates to time recorders. It is of especial value in time recorders for recording elapsed times. It has for its object to provide a simple and efficient time recorder, especially one adapted for recording elapsed times, as for example, between the beginning and the end of a job; a time recorder that will always be in operative position without the necessity of resetting or readjusting and that will be unlimited in capacity within the range of its operations. Our invention is especially useful for recording elapsed times of relatively short duration such as the elapsed time between the beginning and end of a telephone conversation.

In the drawings accompanying this specification and forming part hereof we have shown our improvement as embodied in an elapsed time recorder for recording the length of time of telephone conversations.

Referring to this specific embodiment— Figure 1 is a plan view of a telephone elapsed time recorder;

Fig. 2 is a plan view showing a part of the interior mechanism with the cover broken away for that purpose and with the abutment cylinder in section;

Fig. 3 is a vertical longitudinal section on the lines 3—3 of Fig. 2;

Fig. 4 is a vertical longitudinal section on the lines 4—4 of Fig. 2;

Fig. 5 is a vertical cross-section on the lines 5—5 of Fig. 1;

Fig. 6 is a detail of the handle mechanism on the lines 6—6 of Fig. 3;

Fig. 7 is a vertical section through the punch on the lines 7—7 of Fig. 3;

Fig. 8 is a detail section of the type wheels on the lines 8—8 of Fig. 2;

Fig. 9 is a detail of the ink ribbon feed on the lines 9—9 of Fig. 2;

Fig. 10 shows a card after the first or "in" operation showing a face or top view 55 of the card;

Fig. 11 is a face view of the card after the second or "out" operation;

Fig. 12 is a back view of the card after the "out" operation; 60

Fig. 13 is a diagrammatic view showing the abutment cylinder, the spiral and other parts including the card both at the "in" and "out" positions;

Figs. 14—16 show a modified form of our 65 invention, Fig. 14 being a plan, Fig. 15 a vertical section on the line 15—15 of Fig. 14, and Fig. 16 a detail section on the line 16—16 of Fig. 14; and

Fig. 17 is a detail section showing a cut-out device for the printing pad. 70

Referring to the machine shown in the drawings, 1 is the framework of the machine, 2 a revoluble cylinder mounted in bearings 3 in the framework and provided 75 with a card guide or guideway consisting of a projection from the surface of the cylinder spirally arranged thereon by means of which a card can always be properly positioned in the machine in accordance with the 80 time of the positioning, and 4 represents a clock movement for rotating the cylinder in accordance with the time. We provide a time marker, preferably a punch, for placing a mark upon the card, preferably a 85 punched hole or notch upon the card, representing by its location thereon the time of placing such mark upon the card. We preferably employ two punches presently to be described. These are punches 5, 6. 90

The clock movement may be of any suitable description. In the form shown, 7 is the main spring of the clock movement, 8 the minute arbor revolving once an hour, and 9 the minute recording wheel driven 95 from arm 8 through gears 10, 11, 12 and 13. The minute wheel 9 revolves once an hour. 14 is the hour wheel driven from the minute wheel 9 through cam 15, fast on the shaft of minute wheel 9. This cam in the course of an hour gradually pushes back arm 16 pivoted in the framework at 17 against the pressure of spring 18. At the end of each hour a tooth 19 on arm 16 drops off the cam and causes pawl 20, pivoted at the end 100 of the arm, to feed forward the hour wheel 105

through ratchet 21 fast on the shaft of the hour wheel. 22 is a spring to hold the pawl in engagement with the ratchet.

Cylinder 2 is rotated four times an hour, 5 making a complete rotation in fifteen minutes. The means shown for this purpose consist of gear 23 on shaft 8 meshing with gear 24 on shaft 25 loosely mounted in bearings 26 secured to the framework, a gear 27 10 at the other end of shaft 25 meshing with gear 28 fast on the shaft of cylinder 2, the latter cylinder being loosely supported in bearings 3, 3 of the framework. 30 is a V-shaped projection from the surface of cylinder 2 arranged in spiral shape thereon. It 15 acts as a guide or guideway for properly positioning the card. 29 is a raised edge on the top 34 of the machine to assist the operator in placing the card in proper position with relation to the spiral card guide.

For this purpose, the card 31 is provided with a V-shaped notch 32. A scale 33 is also preferably arranged along one edge of the card, the notch 32 being at the zero of the 25 scale. The scale represents 15 minutes and fifths of a minute. The card is positioned by being placed on the top 34 of the machine with notch 32 placed against the V-shaped abutment of projection 30. It will be understood that this abutment will travel 30 along surface 34 and will therefore position the card along the surface and relatively to the punches and printing mechanism in accordance with the time.

35 is an operating handle for operating shaft 36 through geared sector 37 fast on the shaft 38 of handle 35 and geared sector 39 fast on shaft 36. Shaft 36 operates both 40 of the punches 5, 6 and also the printing pad 40. This is done through a cam 41 on shaft 36 rocking arm 42 fast on shaft 43 and downwardly rocking arm 44 fast on the shaft. Arm 44 carries punch 5. Punch 6 is 45 operated on the other side of the machine through shaft 36 in a precisely similar way. Arm 44 also carries printing pad 40. Thus at every operation of handle 35 the punches and printing pads are actuated.

The operation of the machine is as follows: At the beginning of a telephone conversation the operator slips a card upon surface 34 and brings notch 32 into engagement with the abutment of the spiral and pulls handle 35. This cuts a V-shaped notch 50 in the lower side of the card as shown at 45 in Fig. 10, and at the same time prints on the back of the card the "in" time, as shown at 46 in Fig. 12, where the time printed is "10 19". The distance of the notch 45 from 55 the right of the card as viewed in Fig. 10 represents the "in" time. At the close of the telephone conversation the operator reverses the card, although still keeping the same face up, and slips the "in" time notch 60 45 onto the spiral abutment and pulls the

handle. Thereupon punch 5 punches hole 47 in the edge of the card along the time scale at a point along that scale representing the elapsed time between the first and the second operations of the machine. The 70 distance of the notch 47 along the scale from the inner notch 32 represents the time that has elapsed during the telephone conversation and, as there shown, it is opposite the numeral 5 in the time scale and indicates 75 that five minutes have elapsed. At the same time the "out" time is printed on the back of the card as shown at 48 and as there shown is "10 24". The "in" and "out" times printed on the back of the card furnish 80 a ready means of obtaining such times, if desired, and also furnish a visual test of the accuracy of the operation of the machine.

In Fig. 13 we have given a diagrammatic 85 view representing the position of the parts and the card at two operations where in the "in" operation the projecting abutment or spiral was toward the right of cylinder 2 and in the second operation toward the left. In 90 the "in" operation the abutment was at the point 49. With notch 32 of the card in engagement with it the card extends to the right as shown in dotted lines. The positions of the punches 5 and 6 and the type 95 wheels 9 and 14 are indicated in dotted lines. In this position of the parts the time is represented as being thirteen minutes from the beginning of the revolution of the spiral 30, leaving two minutes of the spiral still to the 100 right of the abutment and notch 32. The position of the parts at the close of the conversation is shown by the card in full lines at the left, the abutment of the spiral being now at point 50. When notch 46 punched 105 in the card at the first operation is now placed over the abutment 50, the card is to the left as shown in Fig. 13. Upon the operation of the handle punch 6 will now punch the notch 47 along the time scale on the 110 other side of the card indicating that three minutes have elapsed during the conversation. In this instance punch 6 and not punch 5 is the one that is operated simply because of the position of the card. It is 115 for this reason that we prefer to employ two punches, thus enabling the machine to be always operative and to be unlimited in its capacity within the range of the machine. In the operation illustrated in Fig. 13 the 120 "in" time was printed upon the back of the card, but the "out" time was not simply for the reason that we have shown only one set of printing wheels and in the "out" operation the card was not in line with them. Of 125 course, if desired, the printing wheels can be duplicated on the other side of the machine and driven synchronously therewith and in that case the "out" time would always be printed.

It will be understood that the two time markers or punches 5 and 6 are spaced apart a distance along the line of travel of the card guide or spiral abutment equal to the 5 length of travel of the card guide and each is adapted when opposite the card to punch a notch or make a suitable mark thereon representing by its location on the card either the time of such marking or the 10 elapsed time between two operations.

The ink ribbon feed mechanism is specially illustrated in Figs. 2, 3 and 9. The ink ribbon extends across the machine, passing over the type wheels in their printing 15 position, and having one end wound on spool 51 and the other on spool 52. The ink ribbon spools are mounted on studs 53 and 54, fixed to the machine. As the ribbon leaves either spool it is embraced by the 20 fingers 55 of the rock lever 56, which is pivotally mounted on the plate 57, at 58. The plate 57 is mounted on studs 59, 59 fastened to the clock frame. Rock lever 56 has an upwardly extending portion 60, which has 25 a bifurcated end coacting with a pin 61 on shift lever 62, pivotally mounted on plate 57. Shift lever 62 has two downwardly extending arms 63 and 64, arranged so as to coact with abutment collars 65 and 66 on 30 shaft 67. Shaft 67 has its ends mounted in studs 53 and 54. A spiral spring 70 has one end attached to the stud 58, on which rock lever 56 is mounted, and its other end is attached to the shift lever 62. Each 35 ribbon spool has mounted with it a gear 71 coacting with a drive gear 72 mounted on shaft 67. Adjacent to the abutment collar 65 is a feed ratchet 73 (see Fig. 9). This ratchet 73 is fed forward by the pawl 74 40 mounted on a plate 75, fixed on the operating shaft 36 of the machine. The pawl 74 has a spring 76 to hold it in contact with the ratchet.

The operation of the inking ribbon feed 45 mechanism is as follows:

The shaft 67 is free to move longitudinally so that in the position shown in the drawings the gear 72 is in mesh with gear 71 on the right hand side (see Fig. 3), and 50 the ribbon is being wound up on spool 52. When the end of the ribbon with the usual thickened part or rivet reaches the left hand fingers 55, the rock lever 56 is gradually carried to a central position, taking with it the shift lever 62, the pin 61 causing this movement. When rock lever 56 has just passed 55 the central position spring 70 exerts its pull on the opposite side of the pivot point of lever 62 and causes rock lever 56 and shift 60 lever 62 to jump to their other position. The arm 63 comes into contact with collar 65 and shifts shaft 67 to the right so as to put gears 71 and 72 on the left, into mesh with each other and disengage gears 72 and 71 65 on the right. Thereupon the ribbon starts

to feed in the other direction. At each operation of the machine pawl 74 feeds ratchet 73 forward one tooth and so rotates shaft 67, and thus feeds the ink ribbon.

Where in any case the distance from the spiral abutment to the right hand end of the cylinder is not sufficient to measure the time that has elapsed the work of recording the elapsed time is taken up by the time marker or punch at the left. In such a case the 70 machine adds to what is left on the cylinder at the right of the spiral abutment, a space or distance from the left hand end of the cylinder to the spiral abutment at the time of the second operation, thus giving the complete elapsed time in every case, irrespective of the location along the cylinder of the abutment either at the time of the "in" operation or at the time of the "out" operation. 75

We are thus enabled to use a short card, and our improved machine can be used continuously and repeatedly for an unlimited number of operations, and elapsed time records up to the range of the machine can 80 always be made. The range of the particular machine shown in the drawings is an elapsed time of fifteen minutes. Our improved machine is accordingly especially useful where the intervals of time to be 85 measured are short, as in a telephone exchange.

The revolute cylinder with its spiral card guide or guideway is in effect a series of card guides connected and movable together, the part of the spiral abutment projecting downward at any time and coacting with the notch in the card being in itself a guide to properly position the card at such time, relatively to the time marker, in accordance 90 with the true time. 100

In Figs. 14-16 we have shown a modification showing another form of a series of card guides connected and movable together. In this form the card guides are shown as 110 abutments 80, each triangular in cross-section and projecting from an endless belt 78 passing over rollers 81 and 82 loosely mounted in the framework of the machine. The endless belt 78 is provided with a row of perforations 79 adapted to engage sprocket teeth 89 on the rollers for advancing the endless belt 78 in accordance with time. 83 is a gear mounted on the minute arbor 8 of the clock movement, meshing with a gear 84 fast with 115 roller 82 and driving that roller and the endless belt 78 in accordance with time. 85 is a cover to protect the steel belt where otherwise it would be exposed. 120

Where the printing pad is operated with 125 no card beneath it, parts are apt to become smutted with ink and to stain the cards in subsequent operations. To prevent this, we preferably employ a cut-out device so that the printing pad will not be operated ex- 130

cept when a card is beneath the pad. We have shown a cut-out device for this purpose in Fig. 17. In this form the printing pad is mounted on one end 88 of a rock lever fulcrumed at 97 in the framework, the other end of the rock lever being a depending arm 95. The rock lever is operated through a cam 90 on operating shaft 36 by means of a depending arm 94 loosely mounted on the fulcrum 97 and through an upright piece 92 pivoted at 98 to an arm 91 loose on stud 87. A spring 99, secured at one end to arm 91 and at its other end to the lower part of upright piece 92, holds that piece against stud 93 on arm 91. A spring 100 is secured at its lower end to an arm 101 loose on stud 87, and at its upper end to swinging piece 86 also loose on stud 87. A cam 96 on operating shaft 36 engages a roller 102 in the end of arm 101, and through spring 100 tends to pull downward the swinging piece 86 into the position shown in dotted lines in Fig. 17. At the same time cam 90 strikes arm 94 and forces it against the upper part 20 of upright piece 92 and against rock lever 95, tending to throw down the printing pad. When a card is in the slot, as shown in Fig. 17, the left-hand end of piece 86 strikes the card. In this position of the parts, spring 30 100 is stretched by cam 96, and the printing pad is thrown down, as above described. If no card is present, however, swinging piece 86 moves downward to the left into the position shown in dotted lines, and carries with it arm 91 which is fast with swinging piece 86. This downward movement causes the upright piece 92 to be moved downward from between the opposing ends of arm 94 and rock lever 95. In this position of the 40 parts, cam 90 merely moves arm 94 idly to the right not coming into contact with rock lever 95 and without depressing the pad. It will be seen that the presence of a card is necessary, therefore, to cause the depression of the printing pad.

Our improved device furnishes a simple and efficient means for computing and recording elapsed time between two operations. In its preferred form the work is 50 accomplished by cutting two notches on the edge of a card, the first one indicating the "in" time, and the second by its location on the card representing the travel of the cylinder from the "in" time to the "out" time, 55 or in other words, representing the elapsed time between the two operations. The term "card" as used herein, is used broadly to indicate any recording surface capable of coacting with the other parts. It may be 60 made of any suitable material, size or form. The clock-controlled means employed herein may be of any suitable kind, whether driven directly by a clock or merely controlled by the clock movement, or whether 65 the devices operate mechanically or elec-

trically. The time markers are shown as punches, and the marks made by them as notches, but any other suitable form of time marker or mark may be employed.

Many other changes and modifications, 70 than those herein specifically referred to, from or in the devices shown in the drawings, may be made without departing from our invention.

What we claim as new and desire to secure 75 by Letters Patent is:

1. In an elapsed time recording machine, the combination of a card guide adapted when in operative position itself to properly position a card relative to two time markers 80 in accordance with time, clock controlled means for moving the card guide, and two stationary time markers spaced apart a distance along the line of travel of the card guide equal to the length of travel of the 85 card guide, and each adapted when opposite the card to make a mark thereon representing by its location on the card the time of such marking or the elapsed time between the two operations. 90

2. In an elapsed time recording machine, the combination of a card guide adapted when in operative position itself to properly position a card relative to two time markers in accordance with time, clock controlled 95 means for moving the card guide, two stationary time markers spaced apart a distance along the line of travel of the card guide equal to the length of travel of the card guide, and each adapted when opposite the card to make a mark thereon representing by its location on the card the time of such marking or the elapsed time between two operations, all so arranged that when, on a second operation of the machine, the card is 100 inserted in the reverse way and the time mark made at the first operation is brought into register with the card guide, that one of the time markers, which is opposite the card will make a time mark upon the opposite side of the card from the first mark, indicating by its location upon the card the elapsed time between two operations. 110

3. In an elapsed time recording machine, the combination of a card guide adapted, 115 when in operative position itself to properly position a card relative to two time markers in accordance with time, clock controlled means for moving the card guide, two stationary time punches spaced apart a distance 120 along the line of travel of the card guide, equal to the length of travel of the time guide, and each adapted when opposite the card to make a mark thereon representing by its location on the card the time of such 125 marking, and a card provided on one side with a time scale, all so arranged that upon a first operation of the machine a time mark will be placed by one of the punches upon the edge of the card opposite the time scale 130

representing by its location on the card the time of the first or "in" operation, and when on a second operation the said time mark is brought into register with the card guide, a 5 time mark will be produced by one of the time punches on the scale side of the card representing by its location on the scale the elapsed time between the two operations.

4. In an elapsed time recording machine, 10 the combination of a card guide adapted when in operative position itself to properly position a card relative to two time markers, clock controlled means for moving the card guide, two stationary time markers spaced 15 apart a distance, along the line of travel of the card guide, equal to the length of travel of the card guide, and each adapted when opposite the card, to make a mark thereon representing by its location on the card the time of such marking or the elapsed time 20 between the two operations.

5. In an elapsed time recording machine, 25 the combination of a spiral card guide for properly positioning a card in the machine, clock controlled means for rotating the card 30 guide so that the card guide will always position a card in the machine in accordance with time, two stationary time markers spaced apart a distance, along the line of 35 travel of the card guides, equal to the length of travel of the card guide and each adapted, when opposite the card, to make a mark thereon representing by its location on the card the time of such marking or the elapsed time 40 between two operations.

6. In an elapsed time recording machine, 45 the combination of a revoluble cylinder, a card guide consisting of a projection therefrom spirally arranged on the cylinder, clock controlled means for rotating the cylinder 50 so that the card guide will always position a card in the machine in accordance with time, two stationary markers spaced apart a distance, along the line of 55 travel of the card guides, equal to the length of travel of the card guide and each adapted, when opposite the card, to make a mark thereon representing by its location on the card the time of such marking or the elapsed 60 time between two operations and a card, all so arranged that when, on a second operation of the machine, the card is inserted in the reverse way and the time mark made at the first operation is brought into register 65 with the card guide, that one of the time markers which is opposite the card will make a time mark upon the opposite side of the card from the first mark, indicating by its location upon the card the elapsed time between the two operations.

7. In an elapsed time recording machine, 70 the combination of a revoluble cylinder, a card guide consisting of a projection therefrom spirally arranged on the cylinder, 75 clock controlled means for rotating the cylinder, two stationary time punches spaced apart a distance, along the line of travel of the card guide, equal to the length of travel of the card guide and each adapted, when opposite a card, to punch a mark thereon representing by its location on the card the time of such punching or the elapsed 80 time between two operations and a card, all so arranged that when, on a second operation of the machine, the card is inserted in the reverse way and the time mark punched at the first operation is brought into register 85 with the card guide, that one of the time punches which is opposite the card will punch a time mark upon the opposite side of the card to the first mark, indicating by its location upon the card the elapsed time between the two operations.

8. In an elapsed time recording machine, 90 the combination of a revoluble cylinder, a card guide consisting of a projection therefrom spirally arranged on the cylinder, clock controlled means for rotating the cylinder 95 so that the card guide will always position a card in the machine in accordance with time, two stationary time punches spaced apart a distance, along the line of travel of the card guide, equal to the length of travel of the card guide and each adapted, when opposite a card, to punch a mark thereon representing by its location on the card the time of such punching or the elapsed 100 time between two operations and a card, all so arranged that upon a first operation of the machine a time mark will be punched by one of the punches upon the edge of the card opposite the time scale representing by 105 its location on the card the time of the first or "in" operation, and, when on a second operation the said time mark is brought into register with the card guide, a time mark will be punched by one of the time punches 110 on the scale side of the card representing by its location on the scale the elapsed time between the two operations.

9. In an elapsed time recording machine, 115 the combination of a revoluble cylinder, a card guide consisting of a projection therefrom spirally arranged on the cylinder, clock controlled means for rotating the cylinder 120 so that the card guide will always position a card in the machine in accordance with time, two stationary time punches spaced apart a distance, along the line of travel of the card guide, equal to the length of travel of the card guide and each adapted, when opposite a card, to punch a mark 125 thereon representing by its location on the card the time of such punching or the elapsed time between two operations, a card provided on one side with a time scale, all so arranged that upon a first operation of 130

the machine a time mark will be punched by one of the punches upon the edge of the card opposite the time scale representing by its location on the card the time of the first or "in" operation, and, when on a second operation the said time mark is brought into register with the card guide, a time mark will be punched by one of the time punches on the scale side of the card representing by its location on the scale the elapsed time between the two operations, and automatic means for printing the "in" time and the "out" time upon the card at the time of such respective operations.

10. In an elapsed time recording machine, the combination of a revoluble cylinder, a card guide consisting of a projection therefrom spirally arranged on the cylinder, clock-controlled means for rotating the cylinder so that the card guide will always position a card in the machine in accordance with time, two stationary time punches spaced apart a distance, along the line of travel of the card guide, equal to the length of travel of the card guide and each adapted, when opposite a card, to punch a mark thereon representing by its location on the card the time of such punching of the elapsed time between two operations, a card provided on one side with a time scale, all so arranged that upon a first operation of the machine a time mark will be punched by one of the punches upon the edge of the card opposite the time scale representing by its location on the card the time of the first or "in" operation, and, when on a second

operation the said time mark is brought into register with the card guide, a time mark will be punched by one of the time punches on the scale side of the card representing by its location on the scale the elapsed time between the two operations, automatic means for printing the "in" time and the "out" time upon the card at the time of such respective operations, and a cut-out device for rendering the printing means inoperative except when a card is present.

11. In an elapsed time recording machine, the combination of a card guide adapted when in operative position itself to properly position a card relative to the time markers, clock controlled means for moving the card guides, two stationary time markers spaced apart a distance along the line of travel of the card guide, equal to the length of travel of the card guide and each adapted, when opposite the card, to make a mark thereon representing by its location on the card the time of such marking or the elapsed time between two operations, automatic means for printing upon the card the time of each operation, and a cut-out device for rendering the printing means inoperative except when a card is present.

In testimony whereof, we have signed our names to this specification, in the presence of two subscribing witnesses.

HARRY T. GOSS.
JAMES W. BRYCE.
